UNITED STATES PATENT OFFICE.

ALPHONSUS GERALD O'FARRELL, OF DUBLIN, IRELAND, ASSIGNOR OF FOUR-SEVENTHS TO JAMES EDWARD SCHUMACHER AND WALTER RICHARD MAKINS, OF YORK, ENGLAND.

CARRIAGE.

SPECIFICATION forming part of Letters Patent No. 644,258, dated February 27, 1900.

Application filed August 30, 1898. Serial No. 689,865. (No model.)

To all whom it may concern:

Be it known that I, ALPHONSUS GERALD O'FARRELL, a subject of the Queen of Great Britain and Ireland, residing in the city and county of Dublin, Ireland, have invented new and useful Improvements in Paper-Carriers and Spacing Mechanism Applicable for Use on Type-Writers or Linotype-Machines and Telegraphic Printing and Recording Instruments, of which the following is a specification.

This invention relates to improved paper-carriers and spacing mechanism applicable for use on type-writing or linotype machines and telegraphic printing and recording instruments; and its object is to provide suitable means or mechanism whereby, say, a sheet of paper may be type-written upon continuously from end to end by, say, for example, any of the well-known forms of type-writing machines having the type mounted, say, on levers or bars or rings or otherwise, but without having to adjust the machine for each line.

In the drawings hereunto annexed, Figure 1 a part plan looking at the top of a type-writing machine constructed according to this invention; Fig. 2, a part end elevation of a machine; Fig. 3, a part front elevation of means employed for imparting a rotary motion to the platen-roller; Fig. 4, a part end elevation of escapement-operating lever; Fig. 5, a perspective back view, showing "dog" or escapement mechanism with upper frame-work of type-writer removed; Fig. 6, a perspective view of platen or paper-carrier applied to, say, a Remington or similar machine.

Similar letters and numerals refer to similar parts throughout the views.

A is a light frame supported and sliding backward and forward laterally on a second frame B for printing capitals by means of the bar b, as in the ordinary Remington machine and operated in a similar manner. In Fig. 2 I show a lever 1 connected to the bar b, and a connection 2, which extends to the shift-key on the keyboard. (Not shown.) The frame B is hinged at its back at B' to the framework

A^x for inspection purposes to the top plate 50 of a machine, say, of the Remington or any other pattern. This arrangement may be modified to suit type-writing machines of almost every pattern.

C is a fixed spindle or shaft supported and 55 its ends held in the bearing c of the frame A, with a portion of its length having a screw-thread cut therein, as shown at c', Fig. 1. The pitch of the screw-thread equals, as a rule, the minimum space between two of the 60 lines of type-writing.

D is a sleeve supported by and rotating on the fixed spindle C, having its ends bushed for this purpose. The sleeve D is free to revolve on the fixed spindle C, and it (the 65 sleeve) is provided with a slot d, cut therein for about, say, half its length in the direction of its axis, immediately over the screw-threaded part c' of the spindle C. A feather d' of or about equal length to the said screw- 70 thread c' projects from the periphery of the sleeve D for purposes to be presently described. This feather d' is placed at an angle to the axis of the sleeve, as shown at Fig. 1. 75

E is the platen or carrier, hereinafter termed a "platen," consisting of a cylinder or barrel mounted on sleeve D, and it is prevented from rotating independently of the said sleeve by means of the feather d', hereinbefore described; but it can slide lengthwise on the sleeve from end to end of the fixed spindle C. The platen on which the paper R is placed is somewhat larger in circumference than the width of the sheet of paper for which the machine is intended to allow for it to be securely fastened to the carrier. The carrier is also somewhat longer than the sheet of paper. To the platen is imparted a revolving and traversing or, in other words, a screw motion, 90 and it has motion for about its own length. It will therefore be obvious that if the platen be revolved over the striking-center of a type-writing machine an imaginary continuous spiral line similar to a screw-thread would 95 be traced thereon.

F is a pin removable at will, but so arranged that it can be fixed in the boss f at

end of platen. The pin F is made to pass through the slot d in the sleeve D and to gear into screw-thread c' of the fixed spindle C for causing the platen to follow the course of the 5 screw on sleeve D. When the sleeve is caused to revolve, the platen will be made to rotate with it, and simultaneously the projecting pin F by its engagement with screw-thread c' will force the sleeve D forward in a longitudinal direction, and thus a screw or spiral motion will be imparted to the platen E. The 10 platen E and sleeve D are rotated by means of a band P on the sleeve, (shown in the drawings at Fig. 1,) by a counter-shaft L, and pulley P, such counter-shaft being driven or actuated by a weight, clockwork, spring, or other motor, a weight N' being shown in the 15 drawings at Fig. 2. The motion is controlled and proper letter-spacing secured by means of a toothed disk fixed to the sleeve in conjunction with an escapement or dog to be now described. H is a disk mounted and fixed to the said sleeve D. On the periphery of the disk H is cut a number of teeth h, say, 20 equal to the number of letters required to fill a line of printing on the sheet R for every revolution of the platen E in addition to allowing the usual space for each letter as is usually provided in type-writing. A few of 25 the teeth h may be omitted at h', Fig. 2, to leave a space which corresponds with the margin or lap of sheet where no printing is required.

I is a small shaft arranged, say, at a right 30 angle to the fixed spindle C and armed with a handle I', capable of being rocked by means of bevel-gears I', mounted, respectively, on shafts I and J. The shaft J is connected by lever I² and link X to the keyboard A', as 35 hereinafter described. A spring I³ (shown at Figs. 2 and 4) is provided to return the shaft I to its normal position after each operation or stroke of the keyboard and on the release of the keys.

40 On the shaft I is mounted an escapement or dog consisting of two similar halves K K', formed of rather wide pieces of metal having their edges curved radially from the center of rocking shaft I and also formed to 45 suit the shape of tooth on disk H. The portion K of the dog is always rigid, while its other part K' has a tendency to advance in direction of arrow 1 on being actuated by means of a flat spring K², (shown at Fig. 2,) 50 which is capable of adjustment by set-screw K³, and thus forms a kind of spring pawl or dog. The part K' of the dog is held normally 55 in contact with the tooth by means of the spring I³, attached to rocking shaft I. This 60 portion of escapement works as follows: The escapement when in its normal position is drawn toward the right by means of spiral spring I³. The spring part K' is then in contact with one of the teeth h of the disk. By 65 the superior force of the driving-motor, say weight N', it is forced into line with the rigid part K. In the action of pressing a key the

shaft I is rocked toward the left, when the rigid part K of the dog enters the same tooth h that the spring part K' has just left, thus 70 preventing the disk moving while a character is being printed onto the paper R. The spring part K' then being free of the disk H advances or springs forward to the right the 75 distance of a tooth, which on pressure again from the keyboard being removed it enters before the rigid part K leaves its tooth. The recoil of the spiral spring I³ then causes the rigid part K to pass to the right, setting 80 free the tooth which it has been engaging. As the rigid part leaves the tooth the movable part engages the next tooth following. The superior force of the motor-driven escape-wheel H then overcomes the slight resistance of spring of movable part K', which 85 is thereby forced into line with rigid part K, where it is retained. The escapement-disk H will have advanced the space of one tooth during the operation—that is, for each stroke of the keyboard.

90 L is a counter-shaft arranged parallel with the fixed shaft C, mounted in bearings on the framework A and having at one end a drum M, on which a cord N is wound. To the cord N is attached a weight or spring. A weight N' 95 is shown in the drawings at Fig. 2. At the other and opposite end of shaft L is mounted a disk O, provided with three projections O' O² O³ on its periphery. These projections are 100 designed to engage with an arm or pawl I⁴, mounted on shaft I, when it is drawn over sufficiently for the purpose by the keys A' for marginal spacing. The pawl is clear of the teeth of the disk O normally; but on pressing or turning the hand-lever I⁵ (shown at Figs. 105 1 and 2) it is brought in front of the teeth of the said disk, when the main or rigid part K of the escapement-dog is completely withdrawn from the teeth h in the disk H, thus permitting the counter-shaft L to revolve until 110 stopped by the first projection O' of disk O coming into contact with the pawl or lever I⁴.

The shaft L and the sleeve D are shown at Fig. 1 connected together by pulley P and band P' in the proportion of three to one; but 115 any other or equivalent form of transmitting motion, such as spur-gearing, to the said two parts may be employed.

120 A handle Q may be provided for winding up the weight and bringing platen E back into its normal and starting position.

R is the sheet of paper, secured on the carrier by means of rubber bands or clips r. (Shown in the drawings at Fig. 6.)

S is an alarm-bell, and T an adjustable pin 125 mounted in slot T', cut in the face of the disk H, for striking the bell, and thus giving a signal prior to the end of each line being reached.

U is an additional or spacing lever provided 130 at side of machine to which the escapement-gear is connected and actuated by a link X, connected to lever I², mounted on shaft J, as shown at Figs. 2 and 5. It is arranged so that it can be depressed by the keys A' or the usual

spacing lever or bar Y by means of the projection y, fixed to the spacing-lever Y' and acting upon the lever U for ordinary spacing, as shown at Fig. 6; but it can be still further depressed for bringing the arm I⁴ into gear and the portions of the escapement-dog K K' out of action for finishing up the end of a paragraph. The lever Y' is somewhat similar to the arrangement found in a Remington machine, and it is pivoted at the rear of the machine; but it is not directly connected to the spacing-gear, but acts through lever U by pressure by means of projection y, which acts on lever U, as just described. If desired, the handle I⁵ may be used in place of lever U.

The action of the machine will be best seen with reference to the perspective views shown at Figs. 5 and 6. The paper R is mounted on the platen E, which is supported by the sleeve 20 D, said platen being connected to the sleeve as described. The sleeve has on its periphery the long feather d', (shown at Fig. 1,) which insures that the platen and sleeve must rotate together. The platen is not prevented 25 from moving lengthwise on the sleeve. About half of the sleeve has a fairly-wide slot d cut in it, through which passes the pin F, which is carried by the boss f of the platen. The pin F gears into a screw c' of the fixed spindle C, on which the sleeve D rotates. Consequently the rotation of sleeve and platen causes the platen to advance toward one end as it is rotated. In other words, the rotation 30 of the arrangement would cause an imaginary screw-thread to be traced on the surface of platen or paper thereon, the pitch of which equals the pitch of leading-screw on fixed spindle. A sheet of paper R being placed on platen E and retained thereon, say, by rubber bands r and the arrangement fixed over 35 the striking-center of, say, a Remington machine, as each letter is struck the sleeve D rotates with a step-by-step motion and a spiral line of printing is impressed on sheet. In placing the paper on the platen it is fixed 40 somewhat askew, (dependent on pitch of thread of the leading-screw). This insures that when it (the paper) is removed the seemingly-continuous spiral line of printing 45 solves itself into a series of perfectly-parallel lines. The feather d', above referred to, instead of being perfectly coincident with axis of the said sleeve is given a slight angularity, such angularity being dependent on the pitch 50 and lead of the screw. The inclining of the feather d' is for compensating any loss that takes place each time the platen makes a complete rotation and for insuring that the type-written matter may be printed thereon in one 55 continuous spiral line from end to end of the sheet. By placing the vertical edge of the paper on the platen parallel with the feather d', as shown in the drawings, it will be found that when the type-written sheet is received 60 from the platen the type-written matter is in parallel line.

The sleeve D is provided at one end with a

disk H, with its periphery cut into an equal number of teeth to the number of letter-spaces which usually go to form a line of printing for which the machine is designed, a few teeth being removed at h' as they are not required, owing to the margin of sheet coinciding with this point.

The driving power may be by a spring or 75 weight, as previously described, which is applied to a counter-shaft L immediately behind the sleeve D. The said sleeve and counter-shaft are connected together by a band P, arranged to pass over the pulley P', and being geared in the proportion of three to one. The weight N' is wound up onto the pulley M, and the platen E is rotated to the left, which is the starting position, by means of handle Q, as shown at Figs. 2 and 6. 85

The escapement is effected by means of a "dog" somewhat similar to the well-known arrangement on the Remington machine, with the exception that in this invention the dog moves or rocks at right angles to the edge of 90 the toothed disk H, before described. The action of the spring-section K' and a permanent section K is exactly similar to that of the well-known dog-and-rack arrangement of the Remington machine—that is to say, no 95 motion of the sleeve D takes place while the dog is pulled to the left by the action of striking a letter. On the release of the key, however, the dog is returned to the right or normal position by the action of helical spring I³, attached to small handle I⁵, whereby one tooth-space of disk is allowed to pass at each stroke. The dog is mounted on the shaft I, on which is also mounted the handle I⁵, as well as the lever I⁴, and a bevel-wheel I' at its end. This 100 bevel-wheel gears with a similar bevel-wheel I' on a shaft J at right angles to first-named shaft I. The shaft J, which is at back of frame B and supported thereby, carries a lever I², which is connected by link X directly 105 to the spacing-lever U. Each time a key A' is struck the lever U is pulled, the motion being transferred to dog-shaft I by means of bevel-gears I'. Thus the alternate or "rocking" motion is imparted to the section of the 110 dog.

The type-writing machine is provided with a spacing-bar system similar to that usually employed in the Remington machine, a projection y, shown bearing on lever U, being 115 provided in addition. The keys bear on a common bar Z, which is part of lever Y', and which in turn transfers the motion to lever Y' by means of the projection y. The lever systems U and Y' are pivoted to the machine 120 at the rear and are maintained in a given position by means of springs. (Not shown in the drawings.)

On the counter-shaft L is mounted the disk D, provided with the three projections O' O² 130 O³. These projections are capable of being intercepted in their rotation by lever I⁴, which, however, can only be done when the sections of the dog are entirely free from escape-

ment-disk H on the sleeve D. When the dog shaft I has been rocked sufficiently to the left by means of an extra depression of lever U, the dog then leaves the escapement-disk 5 H completely, which in that case would rotate quickly till the platen E has been driven to the end of its traverse; but before the dog can completely leave the escapement-disk H the lever I⁴ is in position to intercept the first 10 of the three projections on disk O, and its motion is arrested. These projections O' O² O³ are so arranged that one will be at the lowest point at the commencement of each line 15 of printing on the sheet R. Three projections are required, owing to the gear between the counter-shaft L and sleeve D being three to one.

The upper part of the platen-frame—that is, frame A—is capable of lateral motion—that is 20 to say, movement from front to rear by means of lever 1 and bar b, which is connected to the keyboard by a flexible or other link 2, as shown at Figs. 2 and 3, for printing capitals, as in the ordinary Remington arrangement, 25 without in any way affecting the escapement, as the said parts thereof are attached to the frame A, as clearly shown at Fig. 6. In this movement from front to rear the shaft I moves also. The rear end of this shaft has a splined 30 connection at 8 with the sleeve 5 of the bevelled pinion I', which sleeve is journaled in the bearing or bracket 6, attached to the frame B. The sleeve 5 is held in the bearing by the collar 7. By this means the shaft 35 I can move longitudinally through the sleeve 5 and bearing 6 as the frame A is moved backward and forward, and thus the parts of this escapement carried by the said shaft I remain in engagement at all times with the ratchet- 40 wheel.

Having now particularly described and ascertained the nature of the said invention and in what manner the same may be carried into practice, I declare that what I claim as my 45 invention, and desire to secure by Letters Patent, is—

1. In a type-writing or printing machine the combination of a shaft rigidly mounted in frame hinged to the top of the framework of 50 the machine, a screw-thread cut in said shaft for a portion of its length, a sleeve mounted upon and free to revolve on said shaft, said sleeve having a longitudinal slot cut in it for a portion of its length, a platen mounted upon 55 said sleeve capable of revolving with and sliding longitudinally upon said sleeve, a pin arranged to pass through a boss on the platen in the slot of said sleeve and to engage with the screw-thread cut in the fixed shaft, a disk 60 mounted upon the said sleeve having teeth cut in the major portion of its periphery, a recess formed in periphery of said disk between the said teeth, a rocking shaft armed at one end with a handle and at the opposite

end with a bevel-wheel and provided below 65 and at right angles to the fixed shaft, a helical spring for returning the rocking shaft to its normal position after each oscillation, an escapement-dog mounted upon said rocking shaft and consisting of a rigid section and an 70 adjustable spring-section, each of said sections being arranged to engage with the teeth cut in the periphery of said disk, a second shaft arranged at right angles to the escapement-shaft and armed with a bevel-wheel arranged to gear with bevel-wheel on the last-named shaft, a lever mounted upon the second shaft, a spacing-lever, and a link for connecting it to the lever on the second shaft, all 75 as set forth.

2. In a type-writing or printing machine the combination of a disk mounted upon the said sleeve having teeth cut in the major portion of its periphery, a recess formed in periphery of said disk between the said teeth, 85 a rocking shaft armed at one end with a handle and at the opposite end with a bevel-wheel and provided below and at right angles to the fixed shaft, a helical spring returning the rocking shaft to its normal position after each 90 oscillation, an escapement-dog mounted upon said rocking shaft and consisting of a rigid section and an adjustable spring-section, each of said sections being arranged to engage with the teeth cut in the periphery of said 95 disk, a second shaft arranged at right angles to the escapement-shaft and armed with a bevel-wheel arranged to gear with bevel-wheel on the last-named shaft, a lever mounted upon the second shaft, a spacing-lever and a link 100 for connecting it to the lever on the second shaft, a lever pivoted to the rear of the machine and armed with a projection for engaging with the spacing-lever, said lever armed with a projection being actuated by the keys 105 and spacing-lever of the machine, a counter-shaft mounted in the hinged frame at the back of and parallel with the platen-shaft and sleeve, a pulley and belt for connecting the counter-shaft and sleeve together, a second 110 pulley mounted upon said counter-shaft upon which a cord is wound, a weight attached to free end of cord, a disk mounted upon said counter-shaft and having projections formed upon its periphery, a lever mounted upon 115 the escapement-shaft arranged to engage with the projections on the last-named disk for intercepting its rotation for marginal spacings, and a handle fixed to the counter-shaft for winding up the weight and returning the 120 platen to its normal position, all as set forth.

In witness whereof I have hereunto set my hand in presence of two witnesses.

ALPHONSUS GERALD O'FARRELL.
